PULLEY SLIDE

Owen D. Premo, Muskegon Heights, Mich.

Application December 22, 1939, Serial No. 310,616

4 Claims. (Cl. 45—77)

This invention relates to telescoping or progressive slides designed primarily for use in connection with drawers, containers or similar sliding objects.

The primary object of the invention is to provide a slide of this character which will support the drawer or object with which it is used, so that the drawer or object may be extended to its full depth.

A further object of the invention is the provision of a slide which will limit the vertical and lateral movement of the drawer or object with which it is used, during the movement of the drawer or object to its open or active position.

A still further object of the invention is to provide means to cushion the movements of the sections of the slides, providing a slide which is practically noiseless.

Another object of the invention is to provide equalizing pulleys so arranged as to insure the extension slides moving in unison.

Still another object of the invention is to provide a pulley progressive slide wherein when the inside channel member is pulled outwardly, the center channel member moves in the same direction but at approximately one-half of the speed, so that when the inside channel member moves outwardly to its entire length, the center channel member assists in supporting the weight of the drawer and its contents, due to the fact that the center channel member is extended only approximately one-half of its length.

With the foregoing and other objects in view, which will appear as the description proceeds, the invention resides in the combination and arrangement of parts and in the details of construction hereinafter described and claimed, it being understood that changes in the precise embodiment of the invention herein described, may be made within the scope of what is claimed, without departing from the spirit of the invention.

Referring to the drawings:

Figure 1 is a side elevational view of a pulley slide constructed in accordance with the invention, one end of the pulley slide being shown in section.

Figure 2 is a longitudinal sectional view taken on line 2—2 of Figure 1.

Figure 3 is a vertical sectional view taken on line 3—3 of Figure 1.

Figure 4 is a sectional view taken on line 4—4 of Figure 1.

Figure 5 is a modified form of the invention illustrating a simplified method of securing the

endless belt or flexible member to the outermost channel member.

Figure 6 is a longitudinal sectional view taken on line 6—6 of Figure 5.

Figure 7 is a sectional view taken on line 7—7 of Figure 5.

Figure 8 is a sectional view taken on line 8—8 of Figure 5.

Figure 9 is an elevational view illustrating a further modified form of the invention.

Figure 10 is a sectional view taken on line 10—10 of Figure 9.

Figure 11 is a sectional view taken through a sliding drawer equipped with slides constructed in accordance with the invention, and illustrating an equalizer used in conjunction with the slides.

Referring to the drawings in detail, the drawer slide as indicated by sheet 1 of the drawings, 20 comprises an outer channel member 5 which is secured to a supporting surface such as a cabinet case, or the like, so that the open side thereof is disposed inwardly. The upper and lower flanges 6 of the outer channel member 5 are formed with grooves 7 extended longitudinally thereof and provided in the inner adjacent surfaces of the flanges. It will of course be understood that the outer channel member 5 is of a length equal to the length of the drawer with 30 which it is used.

The reference character 8 indicates the innermost channel member of the slide and this channel member is secured to the drawer with the open side thereof disposed outwardly. As shown, 35 the channel member 8 is formed with laterally extended flanges 9 that cooperate with the inwardly extended flanges 10 formed on the intermediate channel member 11, the intermediate channel member 11 being of a width to fit within 40 the outer channel member 5 in spaced relation therewith.

Supported within the intermediate channel member 11, are wooden fillers 12 that are formed with bores in which threaded sleeves 13 are 45 positioned, the threaded sleeves providing housings for the threaded spring supports 14 on which the springs 15 rest, the outer ends of the springs 15 accommodating the balls 16. These balls 16 extend through openings formed in the flanges of the intermediate channel member, the openings being of diameters less than the diameters of the balls 16, so that only portions of the balls 16 will extend through the openings, to ride in the grooves 7. Thus it will be seen that the balls will set up frictional contact with the

flanges 6 of the outer channel member, restricting movement of the intermediate slide with respect to the outer channel member.

The wooden filler 12 used in connection with each slide, also is provided with cut-out portions 17 arranged near the opposite ends thereof, the openings providing housings for the pulleys 18.

Bores 19 are also formed in the wooden fillers 12 and accommodate the shafts 20 that are extended through the pulleys, and on which the pulleys operate. Plugs 21 close the upper ends of the bores and hold the shafts 20 in their proper positions within the filler. Operating over the pulleys 18, is a flexible power transmitting member which in the present showing is in the form of a belt 22 secured to the casing or frame in which the drawer is mounted, by means of the pin 23, the pin 23 being shown as extending through the casing or frame, the inner end of the pin being secured to the belt 22. An elongated opening is formed in the intermediate channel member, to accommodate the pin 23 and allow movement of the intermediate channel member with respect to the outer or stationary channel member.

The wooden filler is also provided with a groove 24 in which the belt 22 operates. A pin indicated at 25 extends through the innermost channel member 8 and has its inner end connected with the belt 22. This pin 25 also moves through the groove 24.

In the form of the invention as illustrated by sheet 2 of the drawings, the slide is substantially of an all-metal or plastic character and embodies an outer channel member 26, an inner channel member 27 and an intermediate channel member 28, the outer channel member being secured to the casing or frame, while the innermost channel member 27 is secured to the drawer or container with which the slide is used.

Mounted within the intermediate channel member and disposed adjacent to the opposite ends thereof, are pulleys 29 that are mounted on the shafts 30 shown as extended into openings formed in the intermediate channel member 28. These pulleys 29 are formed with substantially V-shaped grooves in which the V-shaped belt 31 operates.

The pulley 29 at one end of the intermediate channel 28 is mounted on a shaft carried by the yoke 32, the yoke 32 being provided with a threaded opening in which the screw 33 operates, the screw 33 being extended through an opening in the flange 34 formed at one end of the intermediate channel member 28. Thus it will be seen that due to this construction, by rotating the screw 33, an adjustment of the pulley at one end of the intermediate channel member may be had, to tighten or loosen the belt.

A plate 35 is struck from the outer channel member 26 and extends through an elongated opening formed in the intermediate channel member 28, the plate 35 overlying the belt 31. A plate indicated at 36 is struck from the inner channel member 27 and extends inwardly to a point directly under the belt 31. These plates 35 and 36 are formed with cut-out portions extending inwardly from the free ends thereof, the cut-out portions accommodating the lugs 37 that are secured to the belt. Thus it will be seen that as the plate 36 moves outwardly with the drawer, the belt will be moved, to extend the intermediate channel member.

Should it be desired to remove the drawer or container with which the slides are used, it is

only necessary to press the belt inwardly to cause the lugs 37 to move from the cut-out portions of the plates 35 and 36. It will be seen that the slides are now free to be moved with the drawer, releasing the drawer.

In Figure 9 of the drawings I have illustrated a further modified form of the invention, and as shown, the inner channel member which is indicated by the reference character 38 is secured to the drawer, and is provided with an upwardly portion terminating in an outwardly extended longitudinal flange 39.

The inner channel member is provided with a wooden filler 40 formed with vertical bores in which the balls 41 are mounted, the balls 41 being spring-pressed in the same manner as the balls shown in Figures 1 and 2 of the drawings. The intermediate channel member, which is indicated by the reference character 42, is provided with an upwardly extended longitudinal flange 43 that supports the shafts 44 on which the pulleys 45 are mounted. Grooves are formed in the pulleys 45 and accommodate the belt 46.

Plates indicated at 47 and 48 are struck from the channel members 38 and 49 respectively, the channel member 49 being the outer channel member of the slide. Lugs 50 are carried by the outer and inner channel members and extend into cut-out portions of the plates 47, connecting the outer and inner channel members to the belt 46.

The channel members shown by Figure 11 of the drawings are substantially the same as the channel members shown by Figure 10 of the drawings, with the exception that the lower ends of the channel members are formed with extensions that extend under the drawer or container with which the slide is used, the extension of the innermost channel member being indicated by the reference character 51, the extension of the intermediate channel member being indicated by the reference character 52, while the extension of the outermost channel member is indicated by the reference character 53.

As shown, the extension of the intermediate channel member is provided with openings for the reception of the shaft 54 on which the pulley 55 is mounted. The shaft 54 being also supported by the bar 56 that extends across the lower surface of the drawer or slide, connecting the slides at opposite sides of the drawer. This bar 56 also provides a support for the pulley 57 at the opposite side of the drawer.

While only one of these bars 56 is shown, it is to be understood that a similar bar is used at the rear end of the drawer providing a support for pulleys similar to the pulleys 55 and 57 at the front end of the drawer. Belts indicated at 58 are connected to the outer and inner channel members of the slide, and operate over the pulleys, so that movement of one slide or channel member will produce a relative movement of the adjacent channel member, to accomplish the purpose of the invention.

While I have shown and described the slide as used in connection with drawers or containers, it is to be understood that the principle of the invention can be effectively carried out in connection with large and heavy machinery, platforms or the like.

From the foregoing it will be seen that due to the construction shown and described, a movable object supported by the slide, will, when extended, be properly supported and will move freely, regardless of the weight of the movable object.

It will also be noted that when the slide is used as a support for a drawer, the drawer may be extended so that the full length of the drawer is exposed, and easy access to the contents at the inner end of the drawer may be had. In the operation of the slide, it will be obvious that as the inner channel is pulled outwardly, the intermediate channel member moves in the same direction, but at one-half of the speed of the inner channel member, with the result that when the inner channel member is moved outwardly its entire length, the intermediate channel member assists in supporting the weight of the drawer by remaining approximately one-half way in the outside channel member and half-way extended from the inner channel, supporting the inner channel member.

It is believed that in view of the foregoing detail description, a further detail disclosure as to the operation of the various channel members is unnecessary.

What is claimed is:

1. A slide of the class described, comprising an outer channel member, an inner channel member and an intermediate channel member, said outer channel member adapted to be secured to a support, said inner channel member adapted to be secured to a drawer, pulleys mounted within the intermediate channel member, an endless flexible member operating over the pulleys, and means for securing the endless flexible member to the outer and inner channel members, whereby movement of the inner channel member causes a relative movement of the intermediate channel member to extend or retract the inner and intermediate channel members.

2. A slide of the class described, comprising an outer channel member, an inner channel member and an intermediate channel member slidably mounted with respect to each other, a filler 40 mounted within the intermediate channel mem-

ber, said filler having openings, pulleys mounted in said openings, an endless flexible member operating over the pulleys, means for securing the outer channel member to the endless flexible member, means for securing the inner channel member to the endless flexible member whereby movement of the inner channel member produces a relative movement of the intermediate channel member extending or retracting the intermediate channel member.

3. A slide of the class described comprising an outer channel member adapted to be secured to a supporting structure, an inner channel member adapted to be secured to a movable member, 15 and an intermediate channel member, said channel members being slidably mounted with respect to each other, pulleys mounted on the intermediate channel member, an endless member operating over the pulleys, lugs on the endless member, said inner channel member and outer channel member having openings in which the lugs are positioned, connecting the inner and outer channel members to the endless member, and means for restricting longitudinal movement of the channel members with respect to each other.

4. A slide of the class described, comprising an outer channel member, and an inner channel member and an intermediate channel member, 30 said channel members being slidably mounted with respect to each other, means for imparting movement of the inner channel member to the intermediate channel member extending or retracting the inner and intermediate channel members, said means embodying pulleys mounted on the intermediate channel member, and a belt operating over said pulleys, said belt being secured to the outer channel member and inner channel member.

OWEN D. PREMO.
